MANIFOLDING ARTICLE AND METHOD OF
MAKINGMilton C. Stern, Dayton, Ohio, assignor to The
Egry Register Company, Dayton, Ohio, a cor-
poration of Ohio

Application October 9, 1939, Serial No. 298,666

11 Claims. (Cl. 270—52)

My invention relates to a machine and method of loading carbon paper on a web or sheet to provide multiple forms applicable for use in manifolding mechanisms such as billing machines, autographic registers, typewriters and similar devices.

It is an object of this invention to effect a definite saving in carbon paper as used in manifolding mechanism.

10 Another object of this invention is to eliminate the necessity of processing carbon paper in order to rearrange it for enfolding in multiple forms. This eliminates the use of additional machinery for processing carbon paper.

15 Another object is to devise a machine and method of loading carbon paper in the form of individual sheets onto the back of a continuous web or sheet which is to be subsequently written upon and a copy made thereof.

20 Another object is to provide an economical copy sheet for manifolding devices in which the carbon paper or equivalent copy producing means is positioned so as to cover only the writing space provided on the form. In this way a substantial saving in carbon paper is effected without lowering the efficient use of the copy form.

Another object is to provide a novel device for removably positioning sheets of carbon on the reverse side of continuous manifold web forms.

25 Another object is to provide a pack of manifolding material having individual carbon sheets adhering to the underside at spaced intervals along a continuous web and wherein the sheets of carbon are positioned so as to register with all portions of the web upon which markings or writing are to be made.

Another object is to devise improved original 40 and copy papers which are secured together and provided with a notch along one edge of the original paper form whereby the carbon sheet can be readily detached therefrom after use and reattached to another sheet for subsequent use.

45 Although this invention is described with particular reference to carbon paper, it will be understood that this invention is applicable for use with various types of sheets or webs of material in devices or mechanisms of this general nature.

These and other objects will appear from the following description taken in connection with the drawing.

In the drawing:

55 Figure 1 is a diagrammatic perspective view

of the machine of this invention which is adapted to position the carbon sheets on the reverse side of a continuous multiple form previous to folding the same to a pack suitable for use in manifolding devices;

Figure 2 is a perspective view of a portion of the web comprising the spaced forms showing individual carbon sheets spacedly mounted upon the back side of the writing forms;

Figure 3 is a plan view of a web sheet partially broken away showing the spaced forms arranged thereon and having transverse tear-off sections therebetween;

Figure 4 is a sectional view taken on the line 4—4 of Figure 3;

Figure 5 is an enlarged sectional view of the 15 web and attached carbon paper;

Figure 6 is a perspective view illustrating the method of removing the carbon paper from a used form sheet.

General procedure

Referring to the drawing in detail, in Figure 1 there is diagrammatically illustrated a mechanism for loading the carbon sheets onto the reverse side of a web comprising spaced printed forms. This mechanism comprises suitable means for advancing a continuous web designated 10 having the spaced forms 11 arranged on one side. Between each form there is provided a perforated or otherwise weakened tear-off section 12, which section provides a hinge portion for folding the continuous web into the form of a pack 13.

Preferably the paper web or continuous sheet 10 is previously processed so as to provide it with the spaced printed forms and having the tear-off hinge sections formed therebetween. The carbon sheets 14 are then positioned on the reverse side opposite the printed forms. To accomplish this the web 10 as it comes from the press is drawn by suitable gripper rolls 20 and guide roll 21 so as to advance the web over the table 22 with the side of the web opposite the printed forms in upward position. As the web is moved over the table 22 a continuous sheet of carbon paper 25 with the carbon side up is fed transversely thereover from the roll 26 by means of the gripper rolls 27.

In loading the carbon sheet onto the back of the web 10 the carbon sheet is squarely arranged thereover so as to be properly aligned with the paper web forms. The movement of the paper web and carbon sheet is synchronized so that registration of the carbon sheet with the spaced

forms on the opposite side of the web is effected, after which the movement of the web and carbon sheet is momentarily stopped while the carbon sheet is suitably attached and thereafter severed from the continuous carbon sheet roll along the edge of the paper web by means of a knife 28 or other appropriate mechanism as illustrated in Figure 1.

Carbon sheet attaching means

For securing the individual carbon sheets 14 onto the back of the forms making up the continuous web or sheet member 10, a gluing mechanism generally designated 30 is provided. This comprises a glue or adhesive dispensing means 31 which is mounted on a support 32 and arranged in such a manner that the glue dispenser means is suspended centrally over the web 10. The dispensing of the glue or adhesive onto the web is automatically actuated by reciprocation of the lever 33 and coating member 34 to deliver a small quantity of glue or adhesive in the form of a spot 35 onto the back of the web 10. If desired the glue or adhesive may be dispensed in the form of a spray and will be preferably delivered onto the surface of the web 10 centrally between the tear-off sections, as illustrated in Figure 1.

Attached to the opposite end of the lever 33 is a pressing roller 36 which is adapted to be reciprocated about the pivot support means 37 to lightly press the carbon sheet against the glue containing portion of the web and secure it in place. The roller 36 is suitably positioned above the web and carbon sheet by means of the pivot arm 37 which is mounted at the outer end in the uppermost portion of the end plate member 38 which is attached to the table 22. Provision may also be made for vertically and horizontally adjusting the position of the pressing roller 36. In some instances, where the weight of the carbon paper or duplicating medium is sufficient, the use of a pressure means for gluing the carbon to the web may be omitted.

In order to prevent the carbon sheet from contacting the wet glue or adhesive as the carbon is being advanced across the web 10, a reciprocable platform member 40 is arranged to be moved outward over the web and beneath the carbon sheet supporting it out of contact with the glued portion of the web until the carbon sheet is in proper position to be brought in contact with the web. Thereafter the member 40 is retracted, as shown in Figure 1, so as to lower the carbon sheet onto the web in contact with the glue 35. Means for reciprocating the member 40 is effected by the wheel member 42 which carries a crank-pin 43 working in longitudinal slot 44 of the rod 45. The upper end of the rod 45 is slotted to accommodate the pin 46 which is secured to the side of the platform 40. The opposite end of the member 45 is pivoted at 47 so that it can be rocked back and forth so as to reciprocate the platform 40. A similar reciprocating rod member is provided on the opposite edge of the carbon sheet 25 so as to effect smooth operation of the plate member 40.

Driving mechanism

The machine is preferably automatically actuated and is arranged to be operated by a suitable prime mover (not shown) which is arranged to continuously drive the shaft 50 and attached gears 51 and 52 and the two-way clutch gearing generally designated 53. A cam member 54 is provided for controlling the clutch mechanism 53

and is rotated by the gear 52 and connecting shaft 55. Cam roller means 56 is positioned on the shaft 57 and is adapted to contact with the cam surface 58 which is designed to move the fork 59 by means of the attached arm 60 which is pivotally secured to the outer end of the cam roller shaft 57. Reciprocation of the fork 59 actuates the clutch so as to connectingly drive the web and carbon sheet advancing mechanism and when shifted to another position connects the mechanism for positioning the carbon sheet and severing it from the carbon sheet roll.

When the clutch is shifted to the right, as shown in Figure 1, the gear 62 is engaged and driven, which in turn actuates the gear 63, shaft 15 64, driving wheel 65 and reciprocates the knife 28 by means of the member 66 and bellcrank 67. The application of the adhesive, as at 35, and pressing of the roller 36 over the carbon sheet is brought about when the driving connection is made through the member 68 which is attached to one end of the bell-crank 67 and reciprocates the dispenser actuating member 33.

It will be noted that during this operation the web and carbon sheet remain stationary. Upon shifting the lever 59 to the left the gear 70 is engaged by the teeth 71 of the clutch and is rotated. Rotation of the gear 70 brings about movement of the web 10 and carbon sheet 25 by means of the train of gears 71, 72, 73, 74 and 30 connecting shafts 75, 76, 77 and 78. Suitable gearing 80, 81, 82 and 83 is provided for actuating the gripper rolls 27 to draw the carbon sheet 25 from the roll 26 and reciprocate the platform 40. The latter is reciprocated by means of the gear 42 which is rotated by the gear 83 to swing the member 45 back and forth and slidably engage the pin 46 to reciprocate the platform 40.

It will be observed that by means of the cam 54 and associated mechanism the feeding of the 40 web and carbon sheet in position to be glued together and the glue dispensing and carbon cutting operations are performed automatically and in the proper sequence.

As illustrated in Figure 6, small notches 85 45 may be made along one edge of the web so that the carbon sheet can be readily grasped and detached from the form after use. Due to the relatively small amount of adhesive which is applied between the sheets, this can be done without un- 50 due strain on the issued form. In this way, if desired, the individual carbon sheets can be removed and used over again.

Further it will be observed that by my method of applying carbon paper to the back of manifold forms, as disclosed herein, a considerable saving of carbon paper is effected. In this instance the carbon paper is disposed over the writing space only, as shown in Figure 4, and the space between the forms, which is not used for 60 writing purposes, as at 86, is left free of carbon paper.

In view of the above description the operation of the machine will be readily understood and further description is believed to be unnecessary.

It will be understood that I desire to comprehend within my invention such modifications as may be necessary to adapt it to varying conditions and uses.

It will be further understood that the attachment of the carbon sheets may be by stapling, adhesives or by interlocking with the paper sheet. Any of these means or any equivalent means may be employed so long as the carbon sheet is posi- 75

tioned as indicated and so long as it is detachable.

It will be understood that this article of manufacture can be produced in a great variety of ways and is not limited to the particular machine shown nor is my invention limited to continuous form sheets.

Having thus fully described my invention, what I claim as new and desire to secure by Letters

10 Patent is:

1. A machine for loading carbon sheet material onto a continuous web at spaced sections along the web, comprising the combination of means for moving said web, means synchronously driven therewith for simultaneously advancing said sheet material over the surface of said web at substantially right angles thereto, and means for attaching at least a portion of said sheet material to said web.

2. A machine for loading carbon sheet material onto a continuous web at spaced sections along the web, comprising the combination of means for moving said web, means cooperating therewith for advancing said carbon sheet material over the surface of said web and substantially of right angles thereto, means for attaching at least a portion of said carbon sheet material to said web, and means associated therewith for rendering inactive the web moving and carbon sheet advancing means during the attachment of said carbon sheet to said web.

3. A machine for loading carbon sheets on a continuous web at spaced sections along said web, comprising common driving means moving said web in loading position and actuating mechanism to advance the end of said carbon sheet over the surface of said web at substantially right angles to the web and in position to be secured thereto.

4. A machine for loading carbon sheets on a continuous web at spaced sections along said web, comprising common driving means moving said web in loading position and actuating mechanism to advance said carbon sheet over the surface of said web in position to be secured thereto, and means comprising a retractable temporary support for lowering said carbon sheet on said web.

5. In a machine for attaching sheets of duplicating paper to the underside of a web of material which is to be subsequently written upon, comprising common driving means for moving said web while simultaneously advancing a continuous sheet of duplicating paper in position over said web so as to cover the under portion of said web which coincides with space on the other side upon which marking or writing is to be made, means for attaching said continuous duplicating paper sheet to said web and means actuated by said driving means for severing the duplicating sheet along the edge of said web.

6. In a machine for attaching sheets of duplicating paper to the underside of a web of material at spaced intervals which is to be subsequently written upon, means for moving said web while simultaneously advancing a continuous

sheet of duplicating paper at substantially right angles thereto in position over said web so as to cover the under portion of said web which coincides with the space on the other side upon which marking or writing is to be made, means for attaching said duplicating sheet to said web while the web and sheet are in said position, and means for severing said attached duplicating sheet from said continuous sheet.

7. An improved method of loading carbon sheets onto the reverse side of a web having spaced forms on the opposite side, positioning said carbon sheet on said web so as to cover the under portion of said web which coincides with the space on the other side occupied by said forms and severing said carbon sheet along the edge of said web.

8. An improved method of loading carbon sheets onto the reverse side of a web having spaced forms on the opposite side, positioning said carbon sheet on said web so as to cover the under portion of said web which coincides with the space on the other side occupied by said forms, severing said carbon sheet along the edge of said web, and fan-folding the continuous web and attached carbon sheets in the form of a pack.

9. An improved method of attaching sheets of carbon onto the reverse side of a manifold paper web having spaced forms on one side and perforations forming hinge sections therebeneath, comprising bringing said web and carbon sheet material together at substantially right angle alignment so that the carbon sheet is squarely arranged thereover and aligned with one of said forms on the opposite side, and thereafter removably attaching said carbon sheet to said web so that registration of the carbon sheet with the spaced forms is effected.

10. An improved method of attaching sheets of carbon onto the reverse side of a manifold paper web having spaced forms on one side and perforations forming hinge sections therebeneath, comprising bringing said web and carbon sheet material together at substantially right angle alignment so that the carbon sheet is squarely arranged thereover and aligned with one of said forms on the opposite side, removably attaching said carbon sheet to said web so that registration of the carbon sheet with the spaced forms is effected, and thereafter folding said web along the hinge sections into a pack.

11. An improved method of loading carbon sheets onto the reverse side of a web, comprising spaced printed forms and hinge sections therebetween, comprising moving said web in a direction parallel to its longitudinal axis, advancing carbon sheet at right angles thereto, applying adhesive material to a portion of the reverse side of said web, positioning said carbon sheet in contact with said adhesive web surface so that registration of the carbon sheet with the spaced forms on the opposite side of the web is effected, and thereafter folding said web and attached carbon sheets in the form of a pack.
